(57) **CLAIM**

The ornamental design for an industrial robot, as shown and described.

DESCRIPTION

FIG. 1 is a left side elevational view of an industrial robot showing our new design;

FIG. 2 is a right side elevational view thereof;

FIG. 3 is a rear elevational view thereof;

FIG. 4 is a front elevational view thereof;

FIG. 5 is a top plan view thereof;

FIG. 6 is a bottom plan view thereof;

FIG. 7 is a perspective elevational view thereof;

FIG. 8 is a second perspective elevational view thereof;

FIG. 9 is a third perspective elevational view thereof;

FIG. 10 is an enlarged left side elevational view of some elements shown in FIG. 1 thereof;

FIG. 11 is an enlarged rear elevational view of some elements shown in FIG. 3 thereof;

FIG. 12 is an enlarged front elevational view of some elements shown in FIG. 4 thereof;

FIG. 13 is an enlarged top plan view of some elements shown in FIG. 5 thereof; and,

FIG. 14 is an enlarged perspective elevational view of some elements shown in FIG. 9 thereof.

The dashed lines in the drawings depict portions of the industrial robot, which form no part of the claimed design.
